ATTORNEY

UNITED STATES PATENT OFFICE.

CHARLES F. WOOD, OF SUMMIT, NEW JERSEY.

DESIGN FOR LETTERS IN JEWELRY.

SPECIFICATION forming part of Design No. 14,485, dated December 11, 1883.

Application filed September 13, 1883. Term of patent 7 years.

To all whom it may concern:

Be it known that I, CHARLES F. WOOD, a citizen of the United States, residing at Summit, in the county of Union and State of New Jersey, have invented and produced a new and original Design for Letters in Jewelry, of which the following is a specification, reference being had to the accompanying drawing, representing a front view of several of the said letters, and forming a part of this specification.

The leading feature of my said design consists of a combination of scroll-work and one or more birds in the form of a letter. The scrolls are made slender in the general outline of the letter, and the parts that are necessarily heavy in its shape are those that are prefer-

ably distinguished by the body of the bird, which is placed in a position, either flying, sitting, or otherwise, that will conform to the requirement of the letter with which it is combined and of which it forms a part.

This design is applied to sleeve-buttons and other articles of jewelry of the form shown.

I claim—

The design consisting of a sleeve-button or other article of jewelry provided with scrolls and birds in the form of letters, as shown and described.

CHARLES F. WOOD.
